UNITED STATES PATENT OFFICE.

HENRY A. OWEN, OF WHITINSVILLE, MASSACHUSETTS, ASSIGNOR TO THE WHITIN MACHINE WORKS, OF WHITINSVILLE, MASSACHUSETTS, A CORPORATION OF MASSACHUSETTS.

WEFT-FEELER MECHANISM FOR LOOMS.

1,251,687.

Specification of Letters Patent.

Patented Jan. 1, 1918.

Application filed September 23, 1916. Serial No. 121,714.

To all whom it may concern:

Be it known that I, HENRY A. OWEN, a citizen of the United States, residing at Whitinsville, in the county of Worcester and State of Massachusetts, have invented 5 the following described new and useful Improvements in Weft-Feeler Mechanisms for Looms.

This invention is an improvement in 10 feeler motions for looms in which the feeler member is rendered active to call a change in the loom's operation by virtue of its slipping sidewise on the filling, or lengthwise of the bobbin, and at some predetermined 15 stage of exhaustion of the filling, and the invention consists in the organization of such a feeler member with the loom changing mechanism whereby it is relieved of the duty of imparting its movement to all of the 20 call-transmitting elements, especially when slipping, and whereby its side-slipping movement takes place against resistances, spring and frictional, which are small in value and practically non-variable during 25 the life of the mechanism, thereby insuring that the slip shall reliably occur at the desired stage of exhaustion and otherwise improving the action and enhancing the durability of the motion. As will appear 30 from the following description, the present motion operates essentially on the principle of trigger mechanism in that, in its normal position, the feeler member serves to sustain some other element of the call-trans- 35 mittting line,—the part termed controller in the present case—against the pressure of a tensioned spring or other force, and when slipping to what may be called its abnormal position, releases that element and allows 40 the force acting thereon to do the work of moving it and of overcoming the inertia of such other call-transmitting elements as may be employed and thereby renders active the actuating train which produces the 45 change in the loom. The spring force so employed may be as powerful as required to give rapid call transmission without thereby affecting the load on the feeler member because the engaging surfaces of 50 the sustained and sustaining members may be so disposed with reference to their relative movements as to disengage without countering the said force, and in consequence of this facility a reliable and satisfactory action is assured to all the various 55

forms of which the invention is capable. The change accomplished in the loom may be the automatic replenishment of the spent bobbin; or of the shuttle, or the stoppage of the loom, as preferred. 60

In the accompanying drawings:

Figure 1 represents in plan view certain familiar parts of a loom with one form of the invention applied to it;

Fig. 2, a cross section on line 2—2 of 65 Fig. 1;

Fig. 3, a top plan of the same parts showing the feeler in its slipped position and the other parts correspondingly shifted;

Fig. 4, a top plan of the same parts showing the lay in an intermediate position; 70

Fig. 5, which illustrates the automatic resetting of the controller is a cross section on line 5—5 of Fig. 4;

Fig. 6 is a top plan of a modified form of 75 controller and resetter; and

Fig. 7 a cross section thereof on line 7—7.

In the illustrated example of the invention, the related parts of the loom proper, as shown, are the usual breast beam *f* on 80 which the feeler motion is mounted, the knock-off lever *m* fulcrumed on a bracket *p* at the end of the beam, the shipper handle *n* in the slot *o* in said bracket, the weft-fork mechanism *h*, *k*, and *g*, which operates the 85 lever *m* to shift the shipper handle, and the actuating arm 20 and its link extension 21, which arm is arranged to be pushed forwardly by the stroke of the weft hammer *i* when the dog 26 carried by said link extension (and controlled by the mechanism of this invention) is interposed in the path of the hammer, or its striker arm 28. The weft hammer *i*, and the actuating arm 20 with its link 21 and dog 26 constitute well 90 known parts of the train of actuating mechanism which transmits the motion of the hammer to the weft replenishing apparatus (not shown), and such train is herein referred to as the actuating train. The drawings also show a portion of the lay *a* with its shuttle box *c*, which latter has a window *c'* in its forward side. The shuttle *b* also has a window *b'* therein which registers with the shuttle box window *c'* when 105 the shuttle is in place therein, as it is when the lay swings forward or toward the breast beam on each alternate, beating up stroke. All these parts are, or may be constructed 110 and organized as commonly found in auto-

matic weft-replenishing looms and the present invention may be variously applied to such or any similar organization.

The side-slipping feeler member, marked 5 1, is pivotally supported upon a carrier 3 mounted on a bracket 5 fastened to the breast beam in front of the shuttle box, and in this position the feeler is adapted to engage the wound mass of filling *e* on the bobbin *d* through the registering windows above referred to, and on each alternate beat-up of the lay. The carrier 3 is mounted to yield when necessary to the forward stroke of the bobbin and for this purpose is constituted, in 10 15 the present case, as a lever pivoted at 4 to the bracket 5 and urged by a spring 7 (connected to a bracket post 8) in the direction to hold the feeler toward the lay. This yielding mounting of the feeler member is 20 25 a preferred means for permitting its contact terminal to perform its feeling function while the lay is still swinging forward. The said contact terminal is shaped preferably as a chisel edge, being adapted to slip on the 30 35 weft or filling, as usual in feelers of this type, and for this purpose the feeler 1 is pivoted at 2 upon its support 3 so that it can turn on a vertical axis. The pivot 2 is offset from the line of push exerted by the 40 45 filling on the contact terminal, so as to establish a tendency for the feeler to swing horizontally or sidewise under the effect of such push. This tendency is normally resisted in part, by a light spring 10 applied to the 50 55 arm 11 on the feeler member and in part and principally, by the condition of firmness of the layers of filling on the bobbin or other filling carrier. When the filling becomes insufficient, by exhaustion to retain the contact terminal at its point of initial contact, the sidewise component of the push on the offset pivot swings the feeler against its spring and causes it to slip on the filling to the position indicated in Fig. 3. Variation 60 65 of the pressure of the spring acting on the feeler will thus vary the point at which slipping will occur and it will be noted that the spring also serves to restore the feeler to normal position after it has slipped and the bobbin has receded as presently described. A stop pin 13 determines this normal position.

The actuating train above referred to and which, as stated, is operated by the stroke 55 60 of the weft hammer arm 28, is controlled by the controller 14, which is a part independent of the actuating train and serves merely to cause the dog 26 to assume a motion-transmitting position in the train whenever a change is called. For this purpose the dog may be variously related to the other parts according to the customary practice in the art, and in the present case it is pivoted at 27 to the link member 21 as above 65 described, the said link being jointed at 22

to the main part of the actuating arm 20. This link rests upon and is adapted to slide when operating, on the upstanding lug 25. By virtue of the gravity of its over-balanced end the dog is normally held in the position 70 shown in Fig. 2, in which position it is out of the path of the weft hammer arm. When tilted on its pivot, its nose portion is lowered so as to be encountered by the said arm and the motion of the weft hammer is thereby 75 imparted to the actuating arm 20 and through the latter to the loom-changing mechanism as will be understood. The controller 14 is a lever extending from the dog at one end to the feeler mechanism at the 80 other end, and oscillates on a pivot 15 which in the present case, is carried by the same carrier member, 3, that carries the feeler proper 1, so that the controller, in the present case, may partake of the normal yielding motion of the feeler and its carrier. The end of the controller adjacent the dog 26 carries an upright pin 31, arranged to strike the pin 30 projecting laterally from the lower part of the dog 26 when the controller 90 moves to an extreme position, as indicated in Fig. 3. By such engagement the dog is tilted so as to be struck by the weft hammer as shown in Fig. 5. The controller lever 14 is normally urged toward this active, change-calling position by a spring 18 connecting it to a hook 19 on the breast beam and the power of the spring is sufficient to give the dog a sharp kick whenever the controller is 95 allowed to act upon it. The momentum of the dog when struck by the controller pin 30 throws its forward end upward and the relative sluggishness with which it returns on its pivotal connection enables the weft hammer to strike it, even though the controller 100 105 be immediately, or coincidently restored to its original position.

During normal operation, the controller is held in inactive relation to the dog by the feeler mechanism and the latter is arranged 110 so that the sidewise slip of the feeler shall release, or cause the release, of the controller and thereby allow the force acting thereon to call the change in the manner just described. For this purpose the feeler mechanism is provided with a controller-sustaining member in the form of an arm or trigger-like projection 12 extending forwardly from the pivoted part of the feeler and into engagement with the surface 16 of the controller, and in such a relation thereto that when the feeler slips the sustaining member 12 shifts to one side and releases the controller, thereby allowing it to assume its active, extreme, or dog-operating position. In 115 the illustration of the invention, the sustaining member 12 also serves to limit the dog-operating swing of the controller when released, as will be apparent in Fig. 3. The bottom of the notch 17, cut in the end of the 120 125 130

- controller adjacent the surface 16, brings up against the end of the trigger member and thereby arrests the controller, and it will of course be understood that the notch is deep enough to permit a sufficient throw of the controller to operate the dog before becoming effective for the purpose stated. According to the organization of the several parts the throw of the controller may be greater or less as desired, but is in any event produced by the force acting on the controller and not by the feeler. The engaging surfaces of the controller and the feeler arm 12, moreover, are disposed substantially parallel to the direction of movement of the latter so that the disengaging or releasing movement takes place without appreciable resistance or friction from the spring pressure and may be made as easy as desired.
- When the controller has been released it is automatically restored to its sustained position by a stroke from the arm 43 which is carried on one end of a short rock shaft 40, journaled in brackets 41 on the rear face of the breast beam. This shaft is rocked at the appropriate instant by an arm 44 at its other end which is struck by the weft hammer near the end of the latter's stroke, following its impact on the dog. The resulting stroke of the arm 43, in a rearward direction, swings the controller far enough to allow the feeler spring 10 to restore the member 12 to its sustaining position, whereupon the feeler and controller are again set and ready to transmit another call to the actuating train of the change producing mechanism. During normal operation the arm 43 oscillates idly and does not strike the controller, the latter being held out of its path by the member 12.
- In the modification of Figs. 6 and 7 the construction will be recognized as similar to that already described, but in this form the controller 14^a operates a secondary lever 14^b pivoted to the feeler bracket at 14^c, and in such manner as to swing the end of the latter rearwardly over the dog 26^a when the controller 14^a is released by the feeler. The dog 26^a is provided with a top cam surface 26^b for engagement by the arm of the lever 14^b when so actuated, and by means of such cam the dog is depressed into the path of the arm 28^a of the weft hammer, the action being otherwise as above explained. Resetting is accomplished in this form by the laterally projecting arm 43^a on the weft hammer, which, near the end of the hammer stroke, strikes the rear side of the lever 14^b and thereby swings the controller 14^a on its pivot 13 far enough to allow the feeler spring 10 to restore the feeler.
- Various other modifications and changes in the specific construction and arrangement of the parts may obviously be made within the spirit and scope of this invention, the essential feature whereof consists, as now fully described, in the release by the feeler of the controller or equivalent member to allow a force acting thereon to transmit the call to the loom-changing or weft-replenishing devices.
- Claims.
1. The combination with a loom having mechanism for producing a change therein including a shiftable dog forming part of the actuating train of said mechanism, of a controller for said dog subject to a force urging it in the direction to call the change and means normally sustaining the controller against said force including a side-slipping feeler having its support offset from the direction of pushing movement on its contact end whereby it is caused to slip by the push of the shuttle contents and adapted by its slipping to release the controller to call the change.
  2. In a loom, a dog adapted for interposition between an actuating member and the loom-changing mechanism to impart the movement of the former to the latter, a controller for said dog, a spring normally urging the controller in the direction to cause such interposition of the dog and means normally sustaining the pressure of the spring including a side-slipping feeler member adapted by its slipping to move said means from its said sustaining relation and allow the controller to move independently under the action of said spring to call the change.
  3. The combination with a loom having an actuating train of mechanism for producing a change therein including a dog in said train, of a controller for said dog, a member normally preventing movement of said controller into action upon said dog, a side-slipping feeler carried on a yielding mounting and caused to slip by the push of the filling and adapted to shift said member by virtue of said slipping movement and thereby permit movement of the controller to call the change.
  4. The combination in a loom of a call-transmitting controller adapted to control the actuating train for producing a change in the loom's operation and being itself independent of said train, a spring adapted to operate said controller in the direction to call the change, feeler mechanism comprising a member normally sustaining said controller in its non-operating position with respect to said train, a side-slipping feeler adapted to shift said member to its non-sustaining position and having a pivotal support offset from the line of push on its contact terminal whereby it may slip on the filling carrier to shift said member, and a carrier for said feeler adapted to yield to the push of the filling carrier on said feeler.
  5. The combination with a loom having a

train of actuating mechanism for producing a change in the operation thereof, of a controller for said train independent thereof and subject to a force urging it in the direction to call the change, means normally sustaining the controller against said force including a side-slipping feeler caused to slip by the push of the shuttle contents and adapted by such slipping to release the controller to call the change and means automatically operating to restore the released controller to its said sustained relation.

6. In a loom the combination of a train of actuating mechanism for changing its operation, a controller for said train independent thereof and subject to force urging it in the direction to render said train active to produce the change and feeler mechanism mounted to yield to the normal push of the filling, said feeler mechanism comprising a member sustaining the controller in an inactive position during the normal yielding movement, a side-slipping feeler member caused to slip on the filling carrier under and by the push thereof and by such slipping adapted to shift said sustaining member from its normal sustaining relation to the controller, whereby the controller is released to cause the change, and means for automatically restoring said controller after it has called the change.

7. The combination with a loom having

a train of actuating mechanism for producing a change in the operation thereof, of a controller for said train independent thereof and mounted to yield to the push of the filling, said controller being subject to a force urging it to an extreme position wherein it renders said train active to effect the change, means normally sustaining the controller against said force and yielding therewith, a side-slipping feeler caused to slip by the push of the filling carrier and by such slipping to release the controller and thereby permit it to call the change.

8. In a loom the combination of a train of actuating mechanism for changing its operation, a controller for said train independent thereof and mounted to yield normally to the push of the filling and having an extreme position wherein it renders said train active to call the change, a feeler carrier also yielding to the push of the filling and a side-slipping feeler on said carrier caused to slip by the push of the filling and provided with means for maintaining said controller and carrier in a determined relative position during their normal movement and permitting the movement to extreme position of said controller when the feeler slips relatively to the filling.

In testimony whereof, I have signed this specification.

HENRY A. OWEN.
